(57) **CLAIM**

The ornamental design for a hydrofoil for a remote controlled toy, as shown and described.

DESCRIPTION

FIG. 1 is a front, right-side, and top view of a hydrofoil for a remote controlled toy showing the new design with its arm in a folded position.

FIG. 2 is a front elevation view of the hydrofoil for a remote controlled toy.

FIG. 3 is a rear elevation view.

FIG. 4 is a right-side elevation view. The left-side is a mirror image of this view.

FIG. 5 is a top plan view.

FIG. 6 is a bottom plan view; and,

FIG. 7 is a front elevation view, with the arm in an extended position.

1 Claim, 6 Drawing Sheets
